UNITED STATES PATENT OFFICE.

WILLIAM C. LAWSON, OF ROANOKE, VIRGINIA.

AEROPLANE.

1,127,651.

Specification of Letters Patent.

Patented Feb. 9, 1915.

Application filed January 3, 1911. Serial No. 600,655.

To all whom it may concern:

Be it known that I, WILLIAM C. LAWSON, a citizen of the United States, residing at Roanoke, in the county of Roanoke and State of Virginia, have invented new and useful Improvements in Aeroplanes, of which the following is a specification.

As a result of investigation and experiments in connection with the problems of aviation, I have reached the conclusion that there are two distinct forces which should be used in lifting and sustaining an aeroplane. One of these forces is the lifting power of the air on coming in contact with a moving plane set at a given angle of inclination, while the other force is the normal upward pressure of the air underneath the plane due to the creation of rarefaction, or a partial vacuum, immediately above the same. I have also found that a proper utilization of both of these forces cannot be obtained from any fixed form or curvature of plane structure. In order to obtain the greatest amount of lifting power from the first named source it is necessary that the underside of the plane be curved so that it will catch and press the air downward without disturbing its continuity or causing same to leave the surface of the planes at angles thereto. While this curvature of the planes is of great value in beginning and ending a flight because of its "grip on the air" as familiarly termed, it is for this very reason, inimical to speed. In order, therefore, to obtain a high degree of speed, it is necessary, after the flight is begun to reduce the curvature of the plane and its resulting "grip on the air" until its underside presents practically a straight surface, whereupon the resulting increase in speed will, with proper plane structure, bring the second named force into use as the sustaining element.

The primary object of the present invention, therefore, is to provide a machine, in which the varying degrees of curvature of the planes which are best adapted for lifting, speeding and landing an aeroplane, may be practically and effectively brought into play at the will of the operator.

A further and important object is to provide a structure which will, in ordinary air currents, maintain lateral stability automatically, and which will also have effective mechanical means at the command of the

operator for maintaining both lateral and horizontal stability.

A still further object is to provide a machine that will be strong and rigid in body structure, and yet have a degree of resilience at its plane extremities in order that it may better accommodate itself to the varying conditions and air currents encountered during progress through the air.

The preferred embodiment of the invention is illustrated in the accompanying drawings, wherein:

Figure 1 is a side elevation of an aeroplane, equipped with the improved apparatus. Fig. 2 is a front elevation of the same. Fig. 3 is a plan view. Fig. 4 is a detail sectional view on an enlarged scale, showing the mechanism for altering the curvature of the elevating and supporting planes. Fig. 5 is a view partially in elevation and partially in section of a portion of one of the rock shafts and the rib operated thereby. Fig. 6 is a detail view of one set of ribs, and indicating in dotted lines the different forms assumed by the plane. Fig. 7 is a detail view showing the mounting for the ribs. Fig. 8 is a view in elevation of a rock shaft, and indicating the different lengths of the crank arms.

Similar reference numerals designate corresponding parts in all the figures of the drawings.

In the embodiment disclosed, a longitudinally disposed body frame 9 is employed, preferably equipped at its front end with a suitable elevating planes 10 which are operated by a longitudinally movable shaft 11, and provided at its rear end with a rudder 12 that may be actuated by cables 12^a extending from the rudder and wrapped in opposite directions upon the shaft 11, which shaft can be rotated. Supporting wheels 13 are journaled on the frame, and the rear portion of said frame is provided with a spring foot 14. A suitable engine 15 is employed, that is geared to propeller mechanism 16. Extending on opposite sides of the body frame is a plane carrying frame, the same comprising upper spaced members 17 and lower spaced members 18, these latter members inclining upwardly and outwardly in divergent relation from the body frame, and being connected at their outer ends to a point near the ends of the members 17. Vertical struts 19 connect the upper and lower

members, and crossed wire braces 20 are arranged between these struts. The said struts are preferably located equal distances apart, and it will therefore be evident, particularly by reference to Fig. 2, that the braces are more nearly vertical at the body frame than at the outer ends of the members 17 and 18. As a result, the truss frame thus produced is more resilient at its ends than at its central portion. By reference to Fig. 6, it will be noted that the front and rear members 17 are connected by stationary ribs 21 so that they will remain in fixed relation.

Mounted on the upper member 17 are oppositely extending planes. Each plane consists of upper and lower sections, the upper section having transverse ribs 22 covered with canvas or other suitable cloth or material 23, the lower section being also provided with transverse ribs 24 carrying on their under sides canvas or other covering 25. The rear portions of the ribs, as shown in Fig. 6, extend underneath and beyond the rear members 17, to which they are pivotally mounted. The front ends of said ribs are pivoted as shown at 26 to plates 27 which plates are, in turn, pivoted, as illustrated at 28 to brackets 29 secured to the front frame member 17.

Extending between the upper and lower sections of each plane is a rock shaft 30, and each rock shaft is provided at the ribs 22 and 24 with oppositely extending crank arms 31. These crank arms are connected by pins 32, on which are journaled rollers 33 that operate against the inner sides of the ribs and move in yokes 34 secured to said ribs. The inner ends of the rock shafts 30 are disposed adjacent to each other, and one of the same carries a sleeve 35 in which the other rock shaft may rotate. These adjacent ends furthermore carry actuating levers 36 provided with suitable dogs 37 that cooperate with racks 38 secured to certain of the cross bars 21. To the rear end of each pair of ribs is connected a guy wire 39 that extends downwardly and passes over a pulley 40 on the main frame, thence upwardly and forwardly being connected to the downwardly extending crank acting on the ribs as shown at 41.

The lower frame members 18 constitute holding means for the lower supporting and bracing planes 42, which incline upwardly and outwardly in opposite directions toward the upper lifting planes.

Taking up now the operation of the machine, by referring to Figs. 4 and 5, it will be noted that when the crank arm 31 is in a substantially horizontal position, the upper plane will have a certain fixed curvature produced by the combined action of the crank arms and the guy wires 39 on the ribs which carry the plane surface covering. On the other hand, when the rock shaft is

turned to bring the crank arms to a more nearly vertical position, then the upper rib is given a greater curvature while the lower rib is brought more nearly straight. It is this variation in the shape or curvature of the planes that is utilized to secure the effects outlined in the preliminary portion of the specification. That is to say, when the machine is at a standstill, and it is desired to start it and elevate it, the planes are placed in the position shown in full lines in Fig. 6, in which case the "grip of the air" is depended upon to cause the elevation of the machine. In other words, the planes will then, on being forced forward at comparatively slow speed, merely glide over the inert body of air beneath them depending for buoyancy on the angle of inclination. As the speed increases, however, and it is desired to secure rarefaction of air above the planes, and at the same time decrease the friction on their under surfaces, the crank arms 31 are moved toward vertical positions, and as a result, the upper section of the plane surface will be given a greater curvature, while the lower or under surface will be made more nearly flat, and its angle of inclination proportionately reduced. This lessening of the angle of inclination will cause the machine as a whole to assume a more horizontal position, thereby causing the front portion of the upper plane surface to incline upwardly and produce a partial vacuum in the air directly in the rear of such front portion, and above the planes as a whole, while there will be no material counteracting friction beneath. The creation of this partial vacuum above the planes proper will cause the planes to be supported by the resulting atmospheric pressure beneath them, and therefore a greater lifting power is secured, and a higher rate of speed obtained, from a given amount of propeller force or driving power. It will also be noted that the variation in curvature can be effected in both planes simultaneously or in each plane independently, and consequently the operator can increase or decrease the lifting and resisting power of either plane which may be necessary to secure lateral stability or facilitate turning.

By reference to Fig. 3, it will be noted that the ribs are of different lengths and that the planes are wider at their intermediate portions than at their ends. It therefore follows that in order to effect a proper and uniform variation in curvature, the different ribs must be bent at different degrees, according to their lengths. This result is secured by having the crank arms 31 of different lengths, as is shown in Fig. 8. The lower planes are employed more particularly for two purposes. They act in the first place as supports, to the upper

planes, and in the second place as stabilizing members. This will be evident when it is considered that if the machine tilts laterally, one or the other of the lower planes 5 will be brought more nearly to a horizontal position, and will consequently produce a greater bearing surface upon the air, while the opposite plane, moving to a more nearly vertical position, presents less 10 porting area, thereby causing the machine to right itself.

From the foregoing, it is thought that the construction, operation and many advantages of the herein described invention 15 will be apparent to those skilled in the art, without further description, and it will be understood that various changes in the size, shape, proportion and minor details of construction, may be resorted to without 20 parting from the spirit or sacrificing any of the advantages of the invention.

Having thus described my invention, what I claim as new, and desire to secure by Letters Patent, is—

25 1. In an aeroplane, the combination with a frame having front and rear supports located in spaced relation to each other, of means connecting the supports for holding them in fixed relation at all times, a plane 30 mounted at its front end on the front support and having an intermediate portion mounted on the rear support, and means engaged with the plane between the supports for varying the curvature of the same 35 between and in rear of the supports while maintaining a fixed distance between the supports.

2. In an aeroplane, the combination with

a frame having front and rear supports, of a plane comprising upper and lower sections 40 having a common pivotal connection at their front ends with the front support and extending on opposite sides of the rear support, and means for varying the curvature of the plane.

3. In an aeroplane, the combination with a support, of a plate pivoted thereto between its ends, upper and lower plane sections pivoted to the plate on opposite sides of its pivot, a rock shaft extending between 50 the sections, and crank arms carried by the shaft and engaging both sections for moving them toward and from each other.

4. In an aeroplane, the combination with spaced relatively fixed plane surface supports, of a plate pivoted between its ends to one of the supports, upper and lower ribs pivoted to the plate on opposite sides of the pivot and slidably engaging the other support, a rock shaft extending between the 55 ribs, and arms carried by the shaft and engaged with the ribs.

5. In an aeroplane, a plane including upper and lower sections, each section having a plurality of bendable ribs of different lengths, a rock shaft extending between the sections, and crank arms of different lengths carried by the rock shaft and engaging the ribs for bending the same.

In testimony whereof I have hereunto set 70 my hand in presence of two subscribing witnesses.

WILLIAM C. LAWSON.
